METHOD OF AND APPARATUS FOR APPLYING METAL SHEATHING TO INSULATED CONDUCTORS

James D. Burby, White Plains, N. Y., assignor to Anaconda Wire & Cable Company, New York, N. Y., a corporation of Delaware

Application May 8, 1937, Serial No. 141,424

21 Claims. (Cl. 29—33)

The present invention relates to improvements in method and apparatus for sheathing electric conductors or cables with ductile metal, such as lead or the like.

5 In my improved method, insulated conductor or conductors are advanced longitudinally through a sleeve or jacketed element, which is cooled, for example, by passing water or other cooling medium therethrough. The sheathing metal in a molten state is fed to an elongated mold surrounding the cooling sleeve and as the sheathing metal cools, it is advanced and later subjected to an operation, which reduces the diameter thereof and brings the sheath into a fairly 10 snug fit with the insulated conductor. The forward feed of the plastic or partially solidified sheath metal, in some cases, will be assisted by rotating the mold and providing it with rifling or thread-like projections on the interior surface 15 thereon. This forward feed will also be assisted by the weight of the metal itself because of the vertical disposition of the apparatus.

In other cases, however, pressure of a head of liquid lead or a suitable inert gas on a supply of 20 sheathing metal will serve to assist in the forward feed thereof.

For a further more detailed disclosure of the invention, reference is to be had to the following specification, the appended claims and the accompanying drawings.

In the drawings—

Fig. 1 is a view partly in elevation and partly in section illustrating novel apparatus for carrying out the improved method; Fig. 2 is an enlarged vertical longitudinal section through that portion of the apparatus in which the sheathing metal is solidified and reduced in diameter; Fig. 3 is an enlarged detail of parts shown in Fig. 2; Figs. 4 and 5 are detached details of parts shown in Fig. 2; Fig. 6 is a section of a swaging head for reducing the diameter of the solidified or partly solidified sheath, the view being taken approximately on line 6—6 of Fig. 2; Fig. 7 is a view similar to Fig. 1 illustrating an alternative embodiment of the invention, wherein the pressure of inert gas is imposed on the body of molten sheathing metal to facilitate the longitudinal feed thereof; Fig. 8 is a detail view illustrating the provision of means for electrically maintaining the sheathing metal in a molten or plastic state.

Referring in detail to the drawings, in accordance with my improved method, a conductor or cable C covered with suitable insulation previously wrapped on or otherwise applied is fed over a 55 guide sheave 10 and downwardly through a cool-

ing device indicated as a whole at 12, through which water or other cooling medium is circulated, the cooling medium being supplied by pipe 14 and carried away by an outlet pipe 16, these pipes being connected with a header 18 having a 5 division wall 20 therein. The header carries a plug 22, to which is secured an elongated piece of guide tubing 24. Surrounding the tubing 24, there is another tube 26. The internal diameter of the tubing 24 is of a size to permit the insulated cable or conductor C to pass freely therethrough and the arrangement of the nested tubes 24 and 26 within the sleeve 12 is such that the cooling medium entering by way of pipe 14 flows downwardly through the space between these two 10 tubes and then upwardly through the annular space between the tube 26 and the outer shell 12 and thence to a suitable discharge point or vessel by way of pipe 16. In this way, a constant body of water or other cooling medium is circulated in 15 heat exchange relationship with the longitudinally advancing insulated conductor or cable so that, as the molten metal sheath is formed thereon in the manner to be presently described, the heat of the molten metal will not have a deleterious effect 20 on the insulation of the conductor or cable.

Molten sheathing material, such as lead or the like is fed from a melting pot 28 into a vessel 30 to the bottom of which is connected an outlet pipe 32, which terminates in a dome-like member 34, 30 which communicates with the interior of an elongated mold 36, to which is keyed a gear 38 by means of which it is rotated by the pinion 40 and shaft 42, the latter being driven through a bevel gearing 44 and 46, from a drive shaft 48 connected with any suitable source of power, such as an electric motor or the like, not shown. The interior of the rotary mold 36 is provided with helical rifling projections 50 and the exterior of the sleeve 12 is provided with one or more longitudinally extending ribs 52. As the mold 36 is rotated, the helical projections 50 exert a screw-like action thereon, which in cooperation with the longitudinal ribs 52 formed on the sleeve 12 acting on the solidified or plastic part of the 40 sheathing metal, tends to feed the sheath metal longitudinally downward. It will be noted that, as the conductor C is being fed longitudinally, the molten sheathing metal is being simultaneously fed therearound and that the rotary mold 45 50 imparts somewhat of a whirling motion to the sheathing metal, but only in the non-solidified portion thereof in the upper part of the mold 36. In the lower part of the mold, where the metal has solidified, it acts as a nut which does not rotate 55

but which is advanced longitudinally by the rifling projections 50 and ribs 52. The forward feed of the sheath metal is assisted by the weight of the metal, the screw-thread like action of the 5 helical projection 50 in cooperation with the longitudinal ribs, thus a sheath of a diameter greater than that of the conductor forms around the latter as it is advanced longitudinally.

A further feature of the present invention 10 relates to the concurrent reduction of diameter in this relatively larger sheath immediately after the metal thereof becomes plastic or solidified. This is accomplished by subjecting the relatively larger diameter portion of the sheath to a swaging operation, whereby the relatively larger diameter sheath is made to make a fairly snug or neat fit with the insulated conductor. To accomplish this, I provide suitable means for working the metal immediately after it has solidified. 15 In the embodiment of the invention illustrated, means for working the metal is in the form of a swaging head, best shown in Figs. 2 and 6. This device includes die portions 54—54, which are adapted to be rapidly reciprocated by hammer portions 56, which coat with rollers 58 carried in a cage member 60, the outer portions of these rollers riding on a hardened race ring 62. The hammers 56 are slideable radially in a groove 64 of a member 66 having an elongated 20 hub 68, to which is keyed a gear 70 and a flywheel 72. The lower end of the hub 68 is mounted in a suitable roller bearing 74 secured in a hub portion 76 of a bracket 78 carried by the frame 79. The gear 70 meshes with the gear 80, 25 which is driven through other transmission gears 82, 84 and 86 from the gear 88 keyed to the shaft 42. The ratio of this gearing will be such as to properly coordinate the speed of the swaging action with the longitudinal feed applied to 30 the sheath by the gearing 38—40, which rotates the mold portion 36.

Extending into the plane of the swaging die members 54 and secured to the lower extremity of the sleeve 12, there is a tapered cap 90, which 35 serves to close the end of the sleeves 12 through which the cooling medium is circulated and which also serves as a lower support for the lower extremity of the innermost tube 24. This cap is tapered so as to properly coat with the converging faces 91 of the reciprocating dies 54 and thus it cooperates with the swaging members in bringing about the gradual reduction of the sheath metal from the large diameter at which it is originally formed to the smaller diameter, 40 to which it is transformed as a result of the swaging operation.

The swaging operation performs a cold or plastic working of the wall of the centrifugally cast sheath metal immediately after it solidifies 45 or has been permitted to become plastic and has the effect of making the resulting sheath more homogeneous than would be the case with a sheath extruded from a thick static annular mass to the finally desired diameter as is the case when the conventional lead press is used.

By my cold working of centrifugally cast metal and simultaneous reduction in diameter of the sheath, I thus improve the characteristics of the resulting cable sheath. My novel method also 50 has the advantage that a much smaller expenditure of power is required to form the sheath to the desired small diameter, than would be the case, where the metal is first allowed to solidify and then extruded by the application of hydraulic or other mechanical pressure thereto. My

method also has the added advantage of making it possible to form a sheath of indefinite length without the inclusion of objectionable joints, seams, laps, welds, or other defects common to the extrusion process.

In some cases, instead of effecting the longitudinal feed of the solidified sheath metal by the use of rifling or screw thread-like projections, as in Figs. 2 and 4, I may provide means for applying a feeding pressure of inert gas to 10 the top of the molten body of metal. Such modification is illustrated in Fig. 7. In this figure, a gas supply tank 90 is connected by pipe 92 having a valve 94 therein for supplying gas to a chamber 96 surrounding a member 98 15 corresponding to the shell 12, shown in Fig. 2. In this modification, the molten metal is supplied from a vessel 30' which is connected by a pipe 32' with a fitting 34', as clearly shown. The vessel 30' may be heated by a gas burner indicated diagrammatically at 100. A pressure of inert gas may be imposed on the body of metal in the vessel 30', there being a pipe 102 connecting the vessel with the gas supply tank 90, this pipe having a control valve 104 therein. 20

Normally, the valves 94 and 104 will be open, thus the pressure of gas from the tank 90 will be exerted at substantially the same unit pressure on the top of the bodies of metal in the chamber 96 and in the vessel 30'. This pressure will tend to assist the longitudinal feed of the sheath being formed by cooperation of the mold 36, which may then be stationary or rotating. When the supply of metal in the vessel 30' becomes depleted, it is merely necessary to 30 shut the valve 104 to permit filling of the vessel without interrupting the operation of the machine, it being apparent that the amount of molten metal in the chamber 96 will be sufficient to permit the machine to operate for a short 35 interval of time while the supply of metal to the vessel 30' is being replenished.

In either of the arrangements of apparatus 40 illustrated in Fig. 2 or 7, heating means may be applied for maintaining the sheath forming metal at the temperature required to maintain the metal in a molten state.

Suitable means for maintaining the metal molten is illustrated in Fig. 8, wherein I have 45 shown an electric heater comprising a heating element 106 carried by a suitable insulator sleeve 108, which is surrounded by an outer casing 110. The mounting for the heater element may be stationary and the mold 36' may be rotated by a gear 38' corresponding to the gear 38 of Fig. 2. In this modification of Fig. 8, the upper portion of the metal holding vessel 112 is provided with an open-topped funnel portion 112, into which the metal may be periodically introduced. The shell 12, gearing for driving the mold and swaging head and other related parts may be regarded as substantially the same as the construction shown in Fig. 2. The molten metal in Fig. 8 will provide a sufficient head or pressure to assist in feeding the solidified sheath downward.

While I have described quite precisely certain specific method steps and a particular combination of instrumentalities used in the method it is 50 not to be construed that I am strictly limited thereto since various changes both in the method steps and in the instrumentalities utilized may be made by those skilled in the art without departure from the invention as defined in the appended claims.

What I claim is:

1. In the manufacture of metal sheathed electric conductors, the method which comprises disposing a body of molten metal around a longitudinally moving insulated conductor, circulating a confined cooling medium in heat exchange relationship therewith in the zone intermediate the conductor and the surrounding molten metal, allowing part of the metal to solidify and thus form a tube-like body of greater diameter than the insulated conductor to be covered, feeding said body longitudinally and subjecting it to forces which materially reduce its diameter. 5
2. In the manufacture of metal sheathed conductors, the method of which comprises longitudinally advancing the conductor to be sheathed, during said advance flowing an annular body of molten metal therearound but spaced radially therefrom, circulating a confined cooling medium in an annular longitudinal zone between the insulated conductor to be covered and the annular molten body of metal, allowing the lower portion of the metal to solidify around the insulated conductor and thereupon subjecting the solidified metal to repeated blows so as to reduce the external diameter thereof substantially or approximately to a size to suit that of the insulated conductor. 10
3. In the manufacture of metal sheathed insulated conductors, the method which comprises advancing an insulated conductor longitudinally downward while disposed in substantially upright position, flowing an annular body of molten metal to a zone spaced radially from the insulated conductor, causing the lower portion of the annular body of metal to solidify while it is moving downwardly and subjecting the solidified metal to an operation effective to reduce the internal diameter thereof to approximately that of the external diameter of the insulated conductor. 15
4. In the manufacture of metal sheathed insulated conductors, the method which comprises advancing an insulated conductor longitudinally downward while disposed in substantially upright position, flowing an annular body of molten metal to a zone spaced radially from the insulated conductor, causing the lower portion of the annular body of metal to solidify while it is moving downwardly and subjecting the solidified metal to a rapid succession of blows at peripherally spaced points so as to reduce the internal diameter of the annular metal body to a size to suit that of the external diameter of the insulated conductor. 20
5. In the manufacture of metal sheathed electric conductors, the method which comprises disposing the body of molten metal around a longitudinally moving insulated conductor, imposing a fluid pressure on said body of molten metal to effect a movement thereof in the direction of feed of the conductor, allowing a portion of the metal to solidify, subjecting the solidified portion to a rapid succession of blows so as to reduce the diameter of the metal body to a size to suit that of the insulated conductor which it encloses. 25
6. In an apparatus for the manufacture of metal sheathed electric conductors, means for disposing a body of molten metal around a longitudinally moving insulated conductor, means for circulating a confined cooling medium in the zone intermediate the conductor and the surrounding molten metal, means for imposing a pressure of gas on one portion of the molten metal while allowing a portion remote therefrom to solidify, and rapidly moving means for subjecting the solidified portion of the metal to forces to reduce its diameter to suit that of the insulated conductor. 30
7. Apparatus of the character described comprising a rotatably mounted mold carrying a body of molten metal, a shell extending longitudinally therethrough, a conductor guide within the shell, means for circulating a cooling medium through the shell and in contact with said guide, means for longitudinally feeding the annular body of metal solidified in the mold and rapidly acting blow applying means effective to reduce the diameter of the tubular body of solidified metal fed from the mold. 35
8. An apparatus of the character described comprising a rotating mold carrying a body of molten metal, a conductor guide extending longitudinally through the mold, cooling means within the mold surrounding the conductor guide, means responsive to the rotation of the mold for longitudinally feeding the annular body of metal solidified therein about the conductor guide and means effective to reduce the diameter of solidified metal fed from the mold. 40
9. An apparatus of the character described comprising a rotating mold carrying a body of molten metal, a conductor guide extending longitudinally through the mold, cooling means within the mold surrounding the conductor guide, means responsive to the rotation of the mold for longitudinally feeding the annular body of metal solidified therein about the conductor guide and rotary swaging means adjacent the exit end of the mold effective to materially reduce the diameter of the tubular body of solidified metal fed therefrom. 45
10. Apparatus of the character described comprising a rotating mold, guide means for an insulated cable extending longitudinally therethrough, means for accommodating a cooling medium circulating in heat exchange relationship with the guide means, means whereby rotation of the mold imparts a longitudinal feed to the tubular body of metal solidified therein, and means disposed adjacent the exit end of the mold for reducing the diameter of the tubular body fed therefrom. 50
11. Apparatus of the character described comprising an elongated mold, a shell extending therethrough, a guide for an insulated conductor extending through the shell, means for circulating the cooling medium through the shell, so as to protect the insulation on the conductor fed through the guide, means for supplying molten metal to the mold, means for rotating the mold and respective means on the interior of the mold and on the exterior of said shell effective upon rotation of the mold to longitudinally advance the metal solidified therein. 55
12. Apparatus of the character described comprising an elongated mold, a shell extending therethrough, a sleeve disposed within the shell serving as a guide for an insulated conductor, means for circulating a cooling medium through the shell so as to protect the insulation on the conductor fed through said sleeve, means for supplying molten metal to the mold, means for feeding the metal solidified in the mold longitudinally thereof and mechanically actuated swaging means adjacent the exit end of the mold effective to reduce the diameter of the annular body of metal emerging therefrom. 60
13. Apparatus of the character described com- 75

- prising an elongated mold, a shell extending therethrough, a guide for an insulated conductor extending through the shell, means for circulating the cooling medium through the shell, so as to protect the insulation on the conductor fed through the guide, means for supplying molten metal to the mold, means for rotating the mold, and respective means on the interior of the mold and on the exterior of said shell effective upon rotation of the mold to longitudinally advance the metal solidified therein and swaging means disposed adjacent the exit end of the mold effective to reduce the diameter of the annular body of solidified metal emerging from the mold.
15. Apparatus of the character described comprising a vertically disposed rotatably mounted mold carrying a body of molten metal, a shell extending longitudinally therethrough, a conductor guide within the shell, means for circulating a cooling medium through the shell and in contact with said guide, means for longitudinally feeding the metal solidified in the mold and rotary swaging means effective to reduce the diameter of solidified metal fed from the mold and common driving mechanism for said mold and said swaging means including gearing whereby the longitudinal advance of the solidified metal effected by the rotation of the mold is properly coordinated with the operation of the swaging means.
20. An apparatus of the character described comprising an elongated mold, a shell extending therethrough, a guide sleeve within the shell for a longitudinally advancing insulated conductor, means for circulating a cooling medium through the shell so as to protect the conductor insulation, means for supplying molten metal to the mold, means for applying gas pressure to the metal within the mold so as to effect the feed of the solidified portion therethrough and flow applying means adjacent the exit end of the mold effective to reduce the diameter of the metal body emerging therefrom.
25. An apparatus of the character described comprising a vertically disposed elongated mold, a shell extending therethrough, a sleeve disposed within the shell serving as a guide for an insulated conductor, adapted to be advanced therethrough, means for circulating a cooling medium through the shell so as to protect the insulation on the conductor fed through the

guide, means in communication with the mold for retaining a body of molten metal and a heating element surrounding said retaining means so as to normally maintain the metal therein in a molten state.

5. 17. The method of forming a continuous metal sheath about an electric conductor, which comprises disposing a body of molten metal around a longitudinally moving insulated conductor, solidifying said metal to a tube-like body of greater inner diameter than the exterior diameter of the insulated conductor, feeding the tube-like body with the insulated conductor, and mechanically reducing the diameter of said tube-like body about said conductor.

10. 18. The method of forming a continuous metal sheath about an electric conductor, which comprises disposing a body of molten metal around a longitudinally moving insulated conductor, solidifying said metal to a tube-like body of greater inner diameter than the exterior diameter of the insulated conductor, feeding the tube-like body with the insulated conductor, and mechanically reducing the diameter of said tube-like body about said conductor to reduce its diameter.

15. 19. The method of forming a continuous metal sheath about an electric conductor, which comprises disposing a body of molten metal around a longitudinally moving insulated conductor, internally cooling said metal to solidify it to a tube-like body moving with said conductor, and 20 swaging said tube-like body to reduce its diameter.

20. The method of forming a continuous metal sheath about an electric conductor, which comprises disposing a body of molten metal around a longitudinally moving insulated conductor, cooling said metal to a tube-like body surrounding and moving with said insulated conductor, and compacting and reducing said moving sheath onto said conductor by pressure applied sidewise 35 40 of said body.

25. 21. Apparatus for forming a continuous metal sheath about a longitudinally moving conductor, which comprises an annular passage through which said conductor passes and having an annular outlet about said conductor, means for supplying molten metal to said passage, means for cooling the metal in said passage, and swaging means at the annular outlet of said passage.
